UNITED STATES PATENT OFFICE.

JESSE LYMAN DANN, OF COLUMBUS, OHIO.

DESIGN FOR A FELLY OR WHEEL-RIM.

SPECIFICATION forming part of Design No. 26,345, dated November 24, 1896.

Application filed October 12, 1896. Serial No. 608,657. Term of patent 14 years.

To all whom it may concern:

Be it known that I, JESSE LYMAN DANN, a citizen of the United States, residing at Columbus, in the county of Franklin and State of Ohio, have invented and produced a new and original Design for Fellies; and I do hereby declare the following to be a full, clear, and exact description of the same, reference being had to the accompanying drawings, forming a part thereof.

In the drawings referred to, Figure 1 shows a felly or rim of a vehicle-wheel shaped according to my design. Fig. 2 is an enlarged perspective view of a portion of the felly or rim, illustrating also the cross-section of the felly.

The inner side of the felly or rim is rounded or convex, as shown at *a*, and the sides *b* are flat and parallel to each other.

The outer side *c* of the felly or rim is flat, 20 with rounded projecting bead *d* extending circumferentially about the felly or rim. The sides of the bead *d* blend by a curve into the flat outer side *c*.

The essential feature of my design is the 25 felly or rim, having its outer surface made with a rounded bead, the sides of which blend by a curve into the said surface.

I claim and desire to secure by Letters Patent—

The design for a felly or rim substantially as herein shown and described.

In testimony whereof I affix my signature in presence of two witnesses.

JESSE LYMAN DANN.
